CHARLES M. BLANCHARD, OF ELYRIA, OHIO.

CYLINDER AND PISTON CONSTRUCTION FOR INTERNAL-COMBUSTION ENGINES.

1,124,839.

Specification of Letters Patent.

Patented Jan. 12, 1915.

Application filed January 22, 1913. Serial No. 743,451.

To all whom it may concern:

Be it known that I, CHARLES M. BLANCHARD, a citizen of the United States, residing at Elyria, in the county of Lorain and State of Ohio, have invented a certain new and useful Improvement in Cylinder and Piston Construction for Internal-Combustion Engines, of which the following is a full, clear, and exact description, reference being had to the accompanying drawings.

This invention relates to the cylinder and piston construction of internal combustion engines, of the type wherein there are two pistons of different diameters connected tandem.

One of the objects of the invention is to provide a light but strong cylinder of simple construction, made of separable parts effectively connected, and having communicating bores.

Another object is to connect the two pistons occupying these bores in such a manner that they may be readily separable, thus allowing easy accessibility of the parts.

Another object is to provide a water circulating system through both pistons in connection with a water jacket in the cylinder around one of them.

A preferred form of my invention is illustrated in the accompanying drawings and is hereinafter more fully described.

In the drawings, Figure 1 is a vertical longitudinal section taken through the cylinder and piston; Fig. 2 is a vertical cross section of the larger cylinder taken on the line 2-2 on Fig. 1; Fig. 3 is a modification of my water circulating system, the same being a vertical longitudinal section of the pistons and cylinder; Fig. 4 is an enlarged section of a portion of the larger piston, shown in Fig. 1, illustrating the packing about the tube conducting the water from the cylinder jacket to the piston, this view being taken substantially on the line 4-4 of Fig. 2.

As shown in the drawings, 10 indicates that portion of the engine frame in which is journaled the crank shaft, and 11 indicates the larger cylinder connected with that frame portion. This cylinder has a comparatively large bore, the outer portion of which receives a cylindrical portion of the smaller cylinder 12. This cylinder 12 has an annular flange 16, by means of which it may be bolted to the cylinder 11; at its front or outer end it has a slightly enlarged bore

closed by a suitable head 20, which is bolted to the cylinder 12 by means of bolts 22, thus forming a combustion chamber in this end of the cylinder. The cylinder 11 is provided with a suitable base 13, which, as shown, may consist of an integral lower portion of the same casting.

Connected pistons 15 and 18 occupy the cylinders 11 and 12 respectively. The piston 15 has a wrist pin 24 suitably held therein, on which is journaled the inner end of a connecting rod 25. This connects with the crank (not shown) on the main crank shaft of the engine carried by the frame 10, in the usual manner.

It will be seen that the cylinder 12 projects into the cylinder 11 for a considerable distance. Registering ports are made through the overlapping walls of the two cylinders. Thus the admission port consists of a passageway 30 in the cylinder 11 and the registering passageway 31 in the cylinder 12, and the exhaust port comprises a passageway 32 in the cylinder 12 and a 30 passageway 33 through the cylinder 11, the latter passageway communicating with an exhaust pipe 34. By making these ports through the overlapping portions of the cylinder and bolting the cylinders together beyond the ports by means of the flange 16 and bolts 17, the weakest portion of the construction, namely, the parts adjacent of the ports in the inner cylinder, is relieved of the working strain caused by the compression and combustion. Accordingly, the walls of this cylinder may be made lighter, and thus may be more easily kept cool by the water jacket hereinafter described.

The cylinder 12 has an inner and an outer wall, the space between which provides a suitable water jacket 35. This jacket is divided by a horizontal diaphragm 36 on both sides of the cylinder and has an intake at 37 and an outlet at 38. The pistons are provided with internal passageways which are in communication with the water space described by means of tubes carried either by the piston or cylinder and slidably projecting into the other member. In the form shown in Fig. 1, the tubes are carried by the inner cylinder and slide in the larger piston. In the form shown in Fig. 3, the arrangement is reversed and the tubes are carried by the larger piston and slide into the inner cylinder.

Referring first to Figs. 1 and 2; at the

inner end of the cylinder 12, and in communication with the water jacket 35, are two tubes 40, having a threaded portion 41, and an angular head 42, by which they may be 5 screwed into the cylinder, as shown. In the piston 15, heretofore mentioned, are two passageways 45 each having an enlarged bore 46 at their inner ends and an intermediate bore 48, which is adapted to receive 10 a suitable stuffing box, embracing a tube 40, and a small bore 50, which fits over the outside of the tube 40. Adjacent to this small bore 50 is a slightly enlarged counterbore which allows this portion of the piston 15 15 to clear the angular head 42 on the tube 40. Fitted into the bore 45 in the inner end of the piston 18 are two tubes 53 having intermediate flanges 55 through which pass cap screws 56 screwing the tubes to the piston. 20 These tubes 53 are larger than the tube 40 and pass over them while leaving a space between them for water.

The stuffing boxes formed around the tubes 40 in the bores 48 are constructed as 25 follows: An inner ring 60 is fitted into the bore 48 and has its edge suitably beveled; next to this ring is packing 61; then comes another ring 62 fitted over the tube 40 and also having a beveled edge. It is held 30 against the packing by means of a spring 64 between the inner end of the tube 53 and said ring 62. This keeps the packing pressed against the tube 40 at a suitable pressure so that it may slide freely along 35 the tube without leakage, while the piston is reciprocated.

Leading from the passageways 45 to the front portion of the piston 15, where it joins the piston 18, are two passageways 66. Registering with these passageways 66 are two passageways 68, in the piston 18, leading forward to a chamber 70 formed at the working end of this piston. This chamber is formed by an inner wall 69, a short distance from the working end. Now, it will 45 be seen that water entering from the pipe 37 and filling the water jacket 35, below the diaphragm 36, will pass through the tube 40, back to the tube 53 to the passageway 66, 50 through the passage 68 and into the chamber 70 in the working end of the piston 18. From this point the course of the water continues via the upper passageway 68 and 66 and through the upper tube 40 into the cylinder jacket and out through the pipe 38. The heating of the water in the chamber 70 55 maintains a continuous flow through the piston, thus keeping them cool. In a vertical engine the water is made to flow through the 60 pistons by using water under pressure at the intake 37.

In order to make the parts conveniently accessible, I secure the piston 15 to the piston 18 by means of bolts 75, Figs. 2 and 3, 65 which screw into the end of the piston 18

and pass through suitable lugs 76 in the piston 15. These bolts are accessible from the open end, and by removing these bolts or cap screws, the two pistons may be separated and drawn out of their respective 70 cylinders, it being only necessary to detach the crank pin from the connecting rod 25 in order to slide these pistons out of their cylinders. This provides a convenient access to the cylinders for cleaning or repairing 75 purposes. With these parts separated, it will be seen, the tubes may be readily removed for any desired purpose, or with the piston 15 removed, the stuffing boxes in the bores 48 may be replaced and the water passages 80 readily cleaned.

The packing of the stuffing boxes in the bores 48 may be readily replaced without removing the piston 15 in the following manner. The tubes 53 are removed and the 85 packing placed inside of a straight tube which is made to slide freely in the bore 46. This tube containing the packing is pushed in till it abuts the shoulder at the inner end of the bore 46, and the packing is then 90 pushed out of it into the position in the bore 48 by means of a smaller tube made to slide freely inside the first tube and over the tube 40.

A slightly modified form of the water 95 circulating system described, is shown in Fig. 3, in which the two bores 80 in the piston 15 extend longitudinally through the piston, having internal threads at the head end of this piston. These threads are adapted to receive the threaded heads 81 on the two tubes 82 corresponding to the two tubes 40 in the form shown in Fig. 1. Inside this head, the opening in communication with the tube may be enlarged and made angular 105 to receive a suitable tool for screwing the head into the piston. The ends of the bores 80 toward the main crank of the engine are closed by means of plugs 83, screwed into the bores. 110

With the two tubes 82 attached to the piston 15 in the manner shown in Fig. 3, it will be seen that the tubes extend into the water jacket 35 of the cylinder 12, and stuffing boxes similar to the stuffing boxes described 115 in connection with Fig. 1, embrace the tubes at the inner end of the cylinder 12. These two rings 84 and 85 are set into a suitable bore 86 having packing between them and are pressing against the packing by means 120 of a spring 87, which presses against the ring 85, and is held in place by a threaded ring 88, screwed into the cylinder at this point and fitting over the tube 82.

To assemble these parts, it is only necessary to remove piston 15 from the cylinder 11 and arrange the stuffing boxes around the tubes 82; then press the piston 15 up against the two heads 81, so that the threads on said heads will engage the corresponding threads 130

in the piston, then insert an angular tool into the head and screw these heads back into the piston 15. Now the bores 80 are closed by means of plugs 83, and the piston 15 secured to the piston 18 by means of the cap screws 75, as heretofore described.

The passages 66 and 68 in this arrangement correspond to the ones described in connection with Fig. 1. Thus, water entering the admission port 37 may circulate through the water jacket 35 through the lower tube 82 and through the passages 66 and 68 into the chamber 70, out through the upper portion of the water jacket 35 and the exit portion 38, as described in connection with Fig. 1. The diaphragm 36 is omitted in this form, water may also circulate around the cylinder without passing through the pistons.

Means of easy access to the stuffing boxes 86 may be made by cutting two openings through the cylinder 11, as indicated by broken lines at 90 and 91, and providing removable plates for normally closing these openings.

It will be seen that the piston 15 forms a crosshead for the connecting rod 25 and if it were not desired to use a second piston, as herein described, the water circulation through the main piston could be provided by making corresponding passages and connections in an ordinary crosshead.

By either of the constructions described, I have provided a very simple, convenient and efficient water circulating system for the cylinders and pistons. I have also provided a light, cheap and strong cylinder construction. The parts are easily assembled and are easily separated whenever occasion requires.

Having thus described my invention, what I claim is:

1. The combination of two cylinders of different diameter, the smaller cylinder being water jacketed, two corresponding pistons operating in said cylinders and connected together, communicating water spaces in the walls of said pistons, the outer portion of the larger piston standing opposite the end of the water jacket in the smaller cylinder, and a sliding tubular connection between the larger piston and the water jacket comprising a tube carried by one of such members and slidably extending into the other.

2. The combination of two cylinders of different diameter arranged tandem, tandem pistons connected together and occupying the cylinders respectively, a chamber within the head of the smaller piston, passageways to and from said chamber in the upper and lower portion of the smaller piston and in the upper and lower portion of the larger piston, said passageways in the larger piston standing opposite the end of the water

jacket of the smaller cylinder, and tubes extending parallel with the axis of the pistons and furnishing communication between the water jacket of the cylinder and the water space of the larger piston.

3. The combination of tandem cylinders of different diameters, connected tandem pistons occupying said cylinders, the smaller cylinder having a water jacket, the end of which is in alignment with the outer portion of the larger piston, water space within the head of the smaller piston, water passageways thereto and therefrom within the walls of the two pistons, and tubes parallel with the axis of the pistons and providing communication between the water jacket and the water space in the larger piston, said tubes being screw threaded near one end into one of said members opposite the water jacket space and extending into the other member, and stuffing boxes carried by said other member and embracing said tubes.

4. The combination of tandem cylinders of different diameters, the smaller cylinder being water jacketed, two pistons in the said cylinders respectively, bolts accessible on the crank side of the larger piston securing it to the smaller piston, communicating water passageways in the walls of the two pistons, and sliding tubular connections between said passageways in the larger piston and the end of said water jacket.

5. The combination of a water jacketed cylinder, a piston therein, a larger piston abutting the end of the main piston, communicating openings within the main piston and said larger piston, tubes in communication with the water jacket and carried by said cylinder parallel with the axis of the pistons and extending into the larger piston, stuffing boxes carried by the larger piston embracing said tubes, and larger tubes carried by the larger piston and freely surrounding the end portion of the tubes first mentioned, said larger tubes being closed at their outer ends.

6. The combination, with two cylinders of different diameters arranged tandem in horizontal position, the smaller cylinder being water jacketed, two pistons in the respective cylinders connected together, communicating water spaces in the two pistons, tubes above and below the axis of the pistons respectively, said tubes being carried by the water jacket and in communication therewith and extending through stuffing boxes carried by the larger piston, and larger tubes forming loose caps over the ends of the tubes first mentioned, said larger tubes being secured to the larger piston.

7. The combination, with a water jacket cylinder, of a hollow piston, means dividing the water jacket into two chambers one above the other, and means for establishing communication between each of said cham-

bers and the chamber of the piston, whereby the water may flow from the lower chamber through the piston to the upper chamber.

8. The combination of two pistons of different diameters secured together, communicating chambers in the two pistons, a water jacketed cylinder for the smaller piston, and sliding tubular connections between the end of the water jacket and the chamber of the larger piston, stuffing boxes surrounding the sliding tubes, one member of the stuffing boxes being slidably mounted, and a spring pressing the same toward its packing.

15. 9. The combination of two pistons of different diameters secured together, communicating chambers in the two pistons, a water jacketed cylinder for the smaller piston, tubes carried by the end of the smaller cylinder in communication with its jacket and extending into the larger piston, tubes of larger diameter carried by the larger piston extending over the end of the tubes carried by the cylinder.

10. The combination of two pistons of 25 different diameters secured together, a water jacketed cylinder for the smaller piston, chambers in the larger piston opposite the end of the water jacket, and sliding tubular connections between said chambers and 30 the water jacket.

11. The combination, with a water jacketed cylinder, of a hollow piston, means for dividing the jacket into an upper and a lower chamber, means for establishing communication between each of said chambers and the chamber of the piston, and means for supplying the water to the lower chamber, whereby it may flow from the lower chamber through the piston to the upper chamber. 40

In testimony whereof, I hereunto affix my signature in the presence of two witnesses.

CHARLES M. BLANCHARD.
